UNITED STATES PATENT OFFICE.

WALTER H. WAKEFIELD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

YARN-IMPINGING, LAY-ACTUATED, BOX-CONTROLLED WEFT DETECTOR.

Application filed March 6, 1925. Serial No. 13,585.

To all whom it may concern:

Be it known that I, WALTER H. WAKEFIELD, a citizen of the United States, residing at Worcester, in the county of Worcester and State of Massachusetts, have invented a new and useful Yarn-Impinging, Lay-Actuated, Box-Controlled Weft Detector, of which the following is a specification.

This invention relates to improvements in weft detectors for box looms and more particularly to the type of detector having a yarn impinging member and a second lay actuated member under control of the box motion. In my co-pending application, Serial No. 758,905, there is shown a detector of this general type having a sliding bar with surfaces of varying heights to engage a portion of the detector. When coarse yarn is being woven the surface which will leave a relatively thick layer of yarn at indication is active and when finer yarn is being woven, another surface which will leave a thinner layer of yarn is active. In the construction such as set forth in said application there is no provision for varying the adjustment, the detector having but two settings.

It is the general object of my present invention to provide means for varying the adjustment of the lay actuated portion of the detector so that the detector can be rendered equally efficient for all combinations of sizes of yarn.

It is a further object of my invention to provide an adjustment which can be set in such position as to permit the use of the same character of yarn in all the shuttles of the loom even though the lay actuated part be controlled by the box motion and moved in time with the active shuttle.

With these and other objects in view which will appear as the description proceeds, my invention resides in the combination and arrangement of parts hereinafter described and set forth in the claims.

In the accompanying drawings wherein I have shown a preferred form of my invention,

Fig. 1 is a front elevation of a portion of a loom having my invention applied thereto, the central portion of the loom being broken away,

Fig. 2 is a top plan view, partly in section, of the detector,

Fig. 3 is a vertical section taken on line 3-3 of Fig. 2,

55

Fig. 4 is an enlarged vertical section on line 4-4 of Fig. 1,

Fig. 5 is an enlarged section on line 5-5 of Fig. 1 showing the control member as it would be used for yarns of varying diameters, and

60

Fig. 6 is a view similar to Fig. 5 but showing the control member set to detect yarns all of which are the same size.

In carrying out my invention I provide a control cam secured to the boxes at one end of the lay and an eccentric roll mounted on the other end of the lay and operatively and adjustably connected to the cam in such a way as to be moved to various positions as the boxes move. Referring more particularly to the drawings it will be seen that I have provided a loom frame 10 having a lay 11 mounted on swords 12 which swing about rocker shaft 13. The left hand end of the lay is provided with upper and lower boxes 14 and 15, respectively, which are connected by a box lifter rod 16 raised and lowered in any approved manner by mechanism not shown.

70

Secured to the inner forward end of the boxes is a cam plate 17 having upper and lower feet 18 and 19, respectively, which are secured to the frame of the boxes as indicated in Fig. 4. The vertical part of said plate is provided with a cam slot 20 which receives a stud 21 secured to the upper end of a lever 22. Said lever 22 is pivotally mounted on a stand 23 secured to the lay 11 and has the lower end thereof connected to a link 24 which extends across the loom. The upper portion of the slot 20 is offset from the lower portion and when the boxes are raised or lowered the stud 21 will be moved toward or from the center of the loom to give a corresponding movement to the connector 24.

85

The opposite end of the lay is provided with a stand 25 on which is pivotally mounted a bell crank lever 26 one end of which is connected to said link 24 and the other end of which is connected to a rod 27 extending upwardly and connected to an arm 28 having a hub 29. Bearings 30 are fixed to the lay as indicated in Figs. 2 and 3 and receive the gudgeons 31 of an eccentric 32. In order to

90

95

100

105

permit said eccentric to be received by the bearings 30 the latter are provided with caps 33. As shown in Fig. 2 the left hand gudgeon 31 has the hub 29 secured thereto by set 5 screw 34, said set screw permitting angular adjustment of the eccentric 32 with respect to the arm 28. From the matter thus far described it will be seen that the longitudinal movement of link 24 will move the eccentric 10 32 angularly about the axis thereof.

The detector employed in connection with my invention is shown more particularly in Figs. 2 and 3 and comprises a stand 35 having an upstanding horn 36 through which 15 projects a controller pin 37 pivotally connected at the forward end thereof to an arm 38. Said arm is secured at the lower end thereof to a shaft 40 supported in bearings 41 and 42 respectively, projecting forward- 20 ly from the stand 35. A second arm 43 is also secured at the lower end thereof to the rod 40 and has the upper end thereof in pressing engagement with a rod 44. Said rod 44 extends through a sliding case 45 25 and is held against offset arm 46 of the detector 47 which is pivotally mounted to the slide 45 at 48 by a coiled spring 49 one end of which is received by the bearing 42 and the other end of which is received by a 30 collar 50 adjustably secured to shaft 40. A second rod 51 is carried by the slide 45 and has the rear end thereof hooked as at 52 to extend around the rear end of said arm 46. Said rod 51 has a head 53 which 35 receives a set screw 54 to engage the bed 55 in which the slide 45 moves.

Upstanding from said slide 45 is a clip 56 through which passes a stud 57 and against which presses a spring 58 interposed between 40 said clip and the cap 59 secured to the bed 55. Depending from the slide 45 is an actuable member comprising an arm 60 in which is adjustably secured a screw 61 having a head 62 positioned for engagement 45 with the eccentric 32.

In operation the spring 58 holds the slide 45 and parts mounted thereon to the rear and spring 49 holds the controller pin 37 under 50 an actuator 63. As the lay beats up on a detecting pick the yarn on bobbin B will engage the detector 47 and prevent the same from turning about the axis 48 thereof under action of spring 49. This results in a forward movement of the slide 45 which 55 will carry the head 62 of the bolt 61 forward so that it will not be engaged by the eccentric 32. When the yarn on the active shuttle has become sufficiently depleted to render replenishment desirable the eccentric 60 32 will engage the head 62 before the yarn engages detector 47 and the latter will be free to swing on its pivot 48 under action of spring 49 as the slide 45 moves forwardly. When this occurs the controller pin 47 will 65 remain under actuator 63 and as the latter

descends an indication of weft exhaustion will be given as set forth in Patent No. 1,030,748.

In looms where a very fine yarn is laid by certain shuttles and a relatively coarse 70 yarn is laid by other shuttles it is desirable that the detector be adjusted so as to leave a smaller thickness of fine yarn and a relatively larger thickness of coarse yarn at the time of indication. This result is accomplished by the mechanism between the boxes and the eccentric, the shifting of the boxes altering the position of the eccentric so that there is more or less horizontal distance between the head 62 and the detector 47, depending upon whether coarse or fine 75 yarn is active. With the construction shown herein it is possible to vary the range of sensitivity of the detector. This adjustment is accomplished by varying the position of the eccentric 32 by means of set screw 34 this adjustment permitting the detector to be used with yarns of varying sizes or 80 yarns all the same size.

Fig. 5 shows the position the eccentric 90 assumes when the detector is cooperating with yarns of varying sizes. The full lines show the setting which the eccentric will assume when cooperating with fine yarn and the dotted lines show the position for coarse 95 yarn. It is desirable that a loom provided with the mechanism shown in Fig. 4 be capable of use with shuttles all of which may carry yarn of substantially the same size, in which case the eccentric 32 will be adjusted as shown in Fig. 6 wherein the full lines show the position of the eccentric for one setting of the lever 22 and the dotted line position shows the setting of the eccentric for the other position of said lever. 100 It will be noted that the horizontal distance between the axis of the eccentric and that portion of the eccentric which engages head 62 is the same for both settings. Thus the 105 detector can remain on the loom while being used as a detector of the usual type.

From the foregoing it will be seen that I have provided a detector for use with a loom having a plurality of boxes for accommodating relatively fine and relatively 115 coarse yarn and that said detector has a variable range of sensitiveness. Also, said detector may be set so as to cooperate with a plurality of shuttles all of which carry 120 yarn of practically the same size.

Having thus described my invention it will be apparent that changes and modifications may be made therein by those skilled in the art without departing from the spirit and scope of the invention, and I do not 125 wish to be limited to the details herein disclosed but what I claim is:

1. In a detector for looms having a plurality of shifting shuttle boxes to accommodate a plurality of shuttles any one of which 130

- may become active, a lay, a yarn impinging member to cooperate with the active shuttle, a lay actuated element operatively connected with the yarn impinging member, a second element mounted on the lay and positioned for operative contact with the first named element, one of said elements being movable in time with the active shuttle to vary the time of contact with the other element as the lay advances, and means independent of the boxes to adjust the setting of one of said elements with respect to the other element.
2. In a weft detector for looms having shifting shuttle boxes, a yarn impinging member to contact with the yarn of an active shuttle, a lay actuated member operatively connected to the yarn impinging member, an eccentric mounted on the lay to cooperate with the lay actuated member, means to vary the position of the eccentric in timed relation with the active shuttle, and additional means to vary the setting of said eccentric with respect to said lay actuated member.
3. In a detector for looms having a plurality of shifting shuttle boxes to accommodate a plurality of shuttles any one of which may become active, a yarn impinging member to cooperate with the active shuttle, a lay actuated member operatively connected to the yarn impinging member, an eccentric mounted on the lay and operatively positioned with respect to the lay actuated member, means connecting the boxes and eccentric to move the eccentric in timed relation with the active shuttle, and additional means to adjust the position of the eccentric with respect to the lay actuated member.
4. In a weft detector for looms having a plurality of shuttle boxes, a yarn impinging member to co-act with the yarn in each shuttle when active, a lay actuated member operatively connected to said yarn impinging member, said lay actuated member including an eccentric, means operatively connecting the eccentric with the shuttle boxes, and additional means to vary the setting of the eccentric with respect to the lay actuated member.
5. In a weft detector for looms having a plurality of boxes to accommodate a plurality of shuttles any one of which may become active, a lay, a yarn impinging member to cooperate with the yarn of the active shuttle, a lay actuated member comprising a pair of elements, one of said elements being operatively connected to the yarn impinging member and the other element being mounted on the lay for operative contact with the other element, one of said elements being angularly movable with respect to the other element under control of the boxes to vary the time of contact between the elements as the lay advances, and means independent of the boxes and active shuttle to vary the points of contact between said elements.

In testimony whereof I have hereunto affixed my signature.

WALTER H. WAKEFIELD.
